(57) **CLAIM**

The ornamental design for a set of vehicle racks as shown and described.

DESCRIPTION

The ornamental design has joints of the appearance and location as shown.

FIG. 1 is a right side elevation view of one of the rack members of the set of vehicle racks;

FIG. 2 is a front elevation view of one of the rack members of the set of vehicle racks;

FIG. 3 is a left side elevation view of one of the rack members of the set of vehicle racks;

FIG. 4 is a top view of one of the rack members of the set of vehicle racks;

FIG. 5 is a rear elevation view of one of the rack members of the set of vehicle racks;

FIG. 6 is a bottom view of one of the rack members of the set of vehicle racks;

FIG. 7 is an exploded view of one of the rack members of the set of vehicle racks;

FIG. 8 is an exploded view of the embodiment shown in FIG. 7 and further showing an alternate position of the top portion;

FIG. 9 is a perspective view one of the rack members of the set of vehicle racks installed in a vehicle; and,

FIG. 10 is a perspective view of one of the rack members of the set of vehicle racks installed in a vehicle.

The broken line showing of environment is for illustrative purposes only and forms no part of the claimed design.
